UNITED STATES PATENT OFFICE

JOHN F. ZIMMERMAN, OF SPRINGFIELD, OHIO

RAILWAY CROSSING

Application filed November 15, 1928. Serial No. 319,492.

This invention relates to railway crossings, it more particularly relating to crossings of the continuous type.

One of the objects of my invention is to provide a crossing of the character referred to which will be simple in construction and effective in operation.

A further object of the invention is to provide a crossing of the continuous type in which bars are employed to close the breaks or spaces between the crossing rails which bars are movable longitudinally of the tracks, in connection with improved means for operating the bars.

15 A further object of the invention is to provide an arrangement by which the bars which close the spaces or breaks in the crossing rails are shifted automatically by a train approaching the crossing.

20 Further objects of the invention will be apparent from the accompanying description and claims.

In the accompanying drawings:

Fig. 1 is a top plan view of a crossing embodying my improvements.

Fig. 2 is an enlarged sectional view on the line 2—2 of Fig. 1.

Fig. 3 is an enlarged sectional view similar to Fig. 2 but with the parts in a different 30 working position.

Fig. 4 is an enlarged sectional view on the line 4—4 of Fig. 2.

Fig. 5 is an enlarged sectional view on the line 5—5 of Fig. 2.

35 Fig. 6 is an enlarged sectional view on the line 6—6 of Fig. 1.

Fig. 7 is an enlarged sectional view on the line 7—7 of Fig. 2.

40 Referring to the drawings, R represents the rails of one track and R' the rails of the other track. Secured to the ties T in spaced-apart relation to the inner sides of and in longitudinal alignment with the respective rails are L-shaped supports 1 of substantially 45 the same height as the rails. Journalled upon a stud 2 projecting from each support 1 is a roller 3 which forms a support for the inner end of a bar 4, which is located between the support and corresponding track rail 50 and is of a width substantially equal to the

space between the support and rail. The inner end 4' of the bar 4 forms a block which is adapted to close the break or space between adjacent track rails and is supported either in the position shown in Fig. 2 to close the 55 breaks or in the inoperative position shown in Fig. 3. The under side of each bar 4 is provided with a cam surface 4'' which cooperates with the roller 3 to raise or lower the bar to operative or inoperative position. 60 The outer end of each bar 4 is formed on an incline as indicated at 4''' and rests upon one arm 5 of a bell crank lever which is pivoted on the stud 6 which projects from the support

1. The other arm 7 of this bell crank lever 65 is pivotally connected by a link 8 with a lever 9 which in turn is pivotally connected with an ear 10 on the under side of the support 1 and is also pivotally connected through the medium of a link 11 with the bar 70 4 adjacent the inner end thereof. The inclined surfaces 4''' of each of said bars, when in the operative position shown in Fig. 2, stand in the path of the flanges of the wheels of an approaching train so that when the 75 flanges strike the inclined portions of the bars the bars are withdrawn from the operative position shown in Fig. 2 to the position shown in Fig. 3 through the medium of the connections described. At the same time, 80 through connections to be described, the other pair of bars of the same track on the opposite side of the crossing are likewise withdrawn and the four bars of the other track projected into operative position so as 85 to close the breaks or spaces between the rails of the track occupied by the approaching train.

In order to cause all of the bars to be simultaneously operated in this manner, each 90 bar is connected to the other bar in the following manner: There is provided at each outer corner of the intersection a lever member consisting of three arms 13, 14 and 15. Each of the arms 13 is connected with the 95 corresponding bar 4 associated with one track and each of the arms 14 is connected with the corresponding bar 4 associated with the other track. Each connection is made through the medium of a link 12, one end of 100

which is pivotally connected to ears 16 on the free end of the arm 13 or 14 as the case may be and the other end of which is pivotally connected with the lever 9. These lever members 13, 14 and 15 are all connected together so that when one pair of lever members is operated the other members will be simultaneously operated and to that end there is provided four links 17, one end of each link being connected with an arm 15 of the corresponding lever member and the other end connected with an arm 13 or 14 of another lever member.

The operation is as follows: Assuming that a train is approaching on the track rails R, the flanges of the wheels riding on the inclined portions 4''' of one pair of the bars 4 depresses the outer ends of those bars and rocks the arms 5 and 7 of the bell crank levers which through the links 8 swing the levers 9 which act through links 11 to withdraw that pair of bars 4, which bars then drop to the position shown in Fig. 3. At the same time by reason of the connection of the levers 9 with the arms 14, all of the lever members are swung so as to retract the other pair of bars 4 associated with the track rail R and project the ends 4' of the two pairs of bars 4 which are associated with the rails R'.

Having thus described my invention, I claim:

1. In a railway crossing, a bar associated with each rail in longitudinal alignment and spaced-apart relation with the inner side thereof, the inner end of said bar forming a block to close the space between rails, the outer end of said bar standing in the path of the flanges of the wheels of a track vehicle so as to be depressed thereby, means for supporting said bar in operative position, and means operated by the depression of said bar and connected therewith for withdrawing said bar from operative position.

2. In a railway crossing, a bar associated with each rail in longitudinal alignment and spaced-apart relation with the inner side thereof, a support for the inner end of said bar including a cam surface on said bar cooperating with said support to raise and lower the bar, the inner end of said bar forming a block to close the space between the rails, the outer end of said bar standing in the path of the flange of a wheel of a track vehicle so as to be depressed thereby, and means operated by the depression of said bar and connected therewith for withdrawing said bar from operative position.

3. In a railway crossing, a bar associated with each rail in longitudinal alignment and spaced-apart relation with the inner side thereof, the inner end of said bar forming a block to close the space between rails, the outer end of said bar standing in the path of the flanges of the wheels of a track vehicle so as to be depressed thereby, means for sup-

porting said bar in operative position, means operated by the depression of said bar and connected therewith for withdrawing said bar from operative position, and means connecting the bars whereby the withdrawal of the bars of one track moves the bars of the other track to operative position.

4. In a railway crossing, a bar associated with each rail in longitudinal alignment and spaced-apart relation with the inner side thereof, a support for the inner end of said bar including a cam surface on said bar cooperating with said support to raise and lower the bar, the inner end of said bar forming a block to close the space between the rails, the outer end of said bar standing in the path of the flange of a wheel of a track vehicle so as to be depressed thereby, means operated by the depression of said bar and connected therewith for withdrawing said bar from operative position, and means connecting the bars whereby the withdrawal of the bars of one track moves the bars of the other track to operative position.

5. In a railway crossing, a bar associated with each rail in longitudinal alignment and spaced-apart relation with the inner side thereof, the inner end of said bar forming a block to close the space between the rails, a support for said bar near the inner end thereof, said bar having an inclined surface supported by said support whereby the longitudinal movement of said bar will raise or lower the same, means operated by an approaching vehicle on one track for moving the bars associated with that track in a direction to permit the depression of the inner ends thereof, and means connecting the respective bars whereby the bars of the other track will be moved longitudinally and raised to operative position.

6. In a railway crossing, a bar associated with each rail in longitudinal alignment and spaced-apart relation with the inner side thereof, the inner end of said bar forming a block to close the space between the rails, a support for said bar near the inner end thereof, said bar having a beveled surface cooperating by said support whereby end-wise movement of said bar will raise or lower the same, means operated by an approaching vehicle on one track for moving the bars associated with that track in a direction to permit the depression of the inner ends thereof, and means connecting the respective bars whereby the bars of the other track will be raised and moved longitudinally to operative position,

said means consisting of a plurality of lever devices located at the outer corners of the rail intersection, the arms of which are connected with the respective bars.

7. In a railway crossing in which tracks cross one another at an angle, tread members for the breaks in the rails of at least one track adjacent the points of intersection with

the other track, said tread members being movable upwardly and downwardly with relation to the rails of the track with which they are associated, and means operated by 5 a vehicle approaching the crossing on the other track to lower said tread members to allow them to clear the wheels of the vehicle.

8. In a railway crossing in which tracks cross one another at an angle, tread members 10 for the breaks in the rail for at least one track adjacent the points of intersection with the other track, said tread members being movable upwardly and downwardly with relation to the rails of the track with which they are associated, and means to lower said 15 tread members to allow them to clear the wheels of a vehicle approaching on the other track, and means for thereafter raising said tread members.

20 In testimony whereof, I have hereunto set my hand this 9th day of November, 1928.

JOHN F. ZIMMERMAN.
